UNITED STATES PATENT OFFICE.

GOTTLOB KLUMPP, OF NEW YORK, N. Y., ASSIGNOR TO ISIDOR MASSE, OF NEW YORK, N. Y.

MARBLE GAME.

1,163,416.

Specification of Letters Patent.

Patented Dec. 7, 1915.

Application filed July 17, 1915. Serial No. 40,475.

To all whom it may concern:

Be it known that I, GOTTLÖB KLUMPP, a citizen of the United States, residing at New York, in the county and State of New York, have invented a new and useful Marble Game, of which the following is a specification.

This invention relates to games; and has for its object to provide a game to be played with marbles in a competitive manner.

The invention is illustrated in the accompanying drawing, in which—

Figure 1, is perspective view of a marble game constructed in accordance with my invention; and, Fig. 2, is a vertical section of the same, taken through one of the channels, and indicating in dotted lines the possible movement of one of the marbles.

In the drawing like numerals of reference refer to the same parts in each of the views.

In practice I provide a game board comprising an inclined plate 3, vertical plate 4, and base plate 5, which latter may be supported by an end plate 6, and by the vertical plate 4, with which it is connected in a manner that it will be inclined sufficiently to cause the marbles to roll down the same by gravity. The plates 3, 4, and 5, are provided with registering channels 7, 8, and 9, respectively, for the guidance of the marble in its descent. The plate 5, is provided with a plurality of pockets 10, which are located in the various channels 9, and are proportioned in size to receive a marble as 11 and hold the same against further descent, as clearly shown. These pockets 10, are less in width than the channels 9, so that a space 12, is left in the channel at each pocket along which the marble may roll past the pocket, and rest against the plate 6.

The operation is as follows: The various pockets 10, are designated by numbers of various values, as clearly shown in Fig. 1; and if a marble 11, lodges in one of these pockets it counts whatever may be the value of that pocket. If, however, the marble passes all the pockets and lodges against the end plate 6, it counts nothing.

As shown in the drawing, I have provided a game with five separate channels. It is supposed that each player will take five marbles and roll one down each of the respective channels. A record is then made of the value of all pockets occupied by marbles, when the pockets are cleared and the

next player repeats the operation. The larger score wins the game.

In operation the plate 5, may be given a greater, or less slant accordingly as the end plate, or support 6, is raised or lowered, as will be understood. The less the slant the more certain are the marbles to enter the pockets as the same will not pass down the channels 9, so rapidly.

It will be observed that while the channels 9, extend to the vertical plate 4, there is no serious obstacle to the marble jumping from the channel which registers with the one in the plate 3, down which it has rolled, to the adjacent channel; and this often happens in practice if the marble is sent down the plate 3, with too much force. This may result to the advantage of the player as the marble may enter a pocket in the next channel of a higher denomination than any contained in the channel down which it would naturally roll.

While I have shown the plates 3, 4, 5, and 6, as made separately and connected together I do not limit myself to such a construction as I am not claiming the exact construction of the device, but a device having the separate plates, or planes disposed in a relative manner, and channeled and provided with pockets as shown, and the channels in the plate, or plane 5, so proportioned in depth that a marble may readily jump from one channel to another when falling from the plate, or plane 3.

I claim:

1. A game comprising two plates, or planes separated a short distance from each other and disposed at an angle to each other and to a horizontal plane, said planes being connected whereby a marble may pass from one to the other, and the lower plane being provided with pockets of various values at intervals of its inclination, for the purpose set forth.

2. A game comprising two plates or planes spaced from each other and disposed at an angle to each other, a third plate or plane connecting said inclined planes and spaced from the upper plane sufficiently to permit a marble to pass therefrom to the lower, and said lower plane being provided with a plurality of pockets of various values.

3. A game comprising two plates, or planes spaced from each other and disposed at an angle to each other, a connecting

plate, or plane spaced from the upper plane sufficiently to permit a marble to pass therefrom to the lower plane, and means to support said lower plane at an angle to the horizontal, said lower plane being channeled, and each channel being provided with a pocket adapted to receive a marble.

4. A game comprising two planes spaced from each other and disposed at an angle to each other, and a connecting plane spaced from the upper plane a distance sufficient to permit a marble to pass therefrom to the lower plane, said lower plane being provided with channels, and each channel being provided with a plurality of pockets less in diameter than the width of the channels, for the purpose set forth.

5. A game comprising two planes spaced from each other and disposed at an angle to a horizontal plane whereby a marble will descend both planes by gravity, and a support for said planes spaced from the upper plane a distance sufficient to permit a marble to pass therefrom to the lower plane, said lower plane being provided with a plu-

rality of channels of limited depth whereby a marble descending from the upper plane may rebound from one channel to another, each channel in the lower plane being provided with pockets of various values and less in width than the width of the channels respectively.

6. The herein described marble game comprising an upper inclined plate, a vertical plate supporting said upper plate and spaced therefrom sufficiently to permit a marble to pass from the upper plate, and a third inclined plate one end of which is supported by said vertical plate and the other end by an end plate, said inclined plates and vertical plate being provided with registering channels, and the channels in the lower plate being provided with pockets less in width than the width of the respective channels, each of said pockets being designated by a numeral of value, for the purpose set forth.

Dated this 14th day of July, 1915.

GOTTLOB KLUMPP.
